PORTABLE DERRICK

Alfred B. Kintzley, Burlingame, Calif.

Application June 24, 1933, Serial No. 677,500

8 Claims. (Cl. 254—139.1)

This invention relates to portable derricks and has for its objects a device of this character especially designed for use in connection with automobiles in such work as raising the transmission or clutch up through the floor opening of the driver's compartment etc., and which will meet the requirement presented by various makes of automobiles. Other objects are extremely simple, cheap, yet rigid construction in such a device.

In the drawing accompanying this specification Fig. 1 is a side elevation of my improved derrick.

Fig. 2 is a plan view of the derrick.

Fig. 3 is an enlarged side view of the hand hoist slidably mounted on the adjustable boom of the derrick.

Fig. 4 is a sectional view of Fig. 3 as seen from line 4—4 thereof.

Fig. 5 is an enlarged vertical section of the adjustable strut engagement on the mast of the derrick.

Fig. 6 is an enlarged cross section of the weight clamped on the hoist cable just above the hook.

Fig. 7 is an enlarged broken side view of one of the legs of the derrick showing its connection to the mast, also the supporting casters.

In further detail my improved derrick consists of two horizontally disposed diverging legs 1, a vertical mast 2, and a boom 3, pivotally secured at 4 to the top of the mast and extending laterally therefrom along a line midway between the legs 1, as best shown in Fig. 2 and in a manner so that the outer end of the boom may swing in a vertical arc 5 and be held firmly at any point by a strut 6 pivoted at its upper end at 7 to a casting 8 which is clamped to the boom, and with its lower end provided with tapered shoe 8 engageable with any of the teeth 9 of a ratchet plate 10 secured to the mast. The teeth 9 are formed at the bottom of a groove in the plate so that the sides of the groove effectually hold the strut from becoming accidentally displaced in a sidewise direction, while a wire spring 11 at the upper end of the strut keeps it resiliently forced into contact with the teeth.

The legs, mast and boom are preferably all made of pipe, and where the mast and two legs join is an angle casting 12 provided with half round seats 13 for the pipes and sockets 14 snugly embracing the ends of the pipes, and all held in rigid assemblage as by means of rivets 15 or welding in place.

Three floor casters 16 form a tripodal support and the casters at the outer end of the legs are mounted in blocks 17 riveted or otherwise secured

to the extreme ends of the legs, while the caster at the mast juncture is mounted in a boss 18 in the angle joint casting 12, all casters being held from dropping out by any suitable means such as the screws 19.

The boom is provided with a casting 20 at its outer end forming two bearing sides between which is a head pulley 21 over which the hoist rope 22 passes, and at the extreme outer end of the casting 20 is an eye 23 or equivalent device 60 for suspending an electric lamp above the work, as it is always dark in working on automobile transmissions, clutches, flywheels, etc.

Rope 22 carries a hook 37 at its free end and just above this a split weight 24 clamped over the doubled back end of the rope so as to suspend the hook and also provide weight enough to pull the rope downward as it is unrolled from the drum 25 of a hand hoist carried between the arms 26 of a bracket 27 carried on the boom 3 and clamped thereto by cooperation with casting 8 as indicated in Fig. 3. The drum is secured to a shaft 28 as is also a ratchet wheel 29. This wheel 29 has two sets of ratchet teeth, one set 30 on its periphery and the other set 31 on its side. Teeth 30 are 70 engaged by a spring pawl 32 to prevent reverse rotation of the drum and side teeth 31 are engaged by a spring pawl 33 carried by a crank handle 34 loosely mounted on the end of the drum shaft 28 and prevented from coming off by a collar or nut 35. A handle 36 connected to pawl 32 serves for lifting it out of engagement so that the drum may be permitted to unwind (under control of the hand crank). With the above arrangement it will be observed that the hand hoist 75 may be adjusted to various positions along the boom, also that this will vary the angle of projection of the boom, but that a separate adjustment of the angle of the boom is had in the ratchet strut connection to the mast.

In using the derrick the two legs are rolled under an automobile and the boom is projected through the open doorway (if a closed car) into the driver's compartment, the hoist is positioned in best place to avoid the door and permit most efficient operation and the boom given the proper angle to clear the dash or instrument board of the car. An electric bulb is suspended from the eye 23 to light the work. The design of the derrick with its hand-operated hoist drum on the boom itself provides for operation by one mechanic from his place inside the car by merely oscillating the ratchet handle without even standing up, and after raising the machinery, he can back the derrick out to 100 105 110

carry the load through the doorway. The spread legs of the derrick being free from cross braces provide a clear space for depositing the load upon the floor or lifting it therefrom.

5 Having thus described my improvements, what I claim is:

1. A portable derrick comprising a pair of horizontally extending V legs close to the floor, a mast rigidly secured at the juncture of the legs, a vertically adjustable boom pivoted to the top of the mast extending laterally on a line between the legs, a hand hoist mounted on said boom forwardly of said mast provided with a hoist rope extending over the end of said boom.
- 10 2. A portable derrick comprising a mast, a pair of horizontally extending legs close to the floor diverging from said mast, a boom extending laterally from said mast above the legs, and a hand-operated hoist mounted on said boom forward of the mast so as to be accessible to an operator under the boom.
- 15 3. In a portable derrick provided with a boom projecting laterally from a mast, a hoist drum mounted on said boom forward of the mast with its rope extending over the end of the boom, and a ratchet hand crank on said drum permitting operation of the drum by oscillating the hand crank from a position below the weight-supporting end of said boom.
- 20 4. A portable derrick comprising a pair of horizontally extending V legs, a mast at the juncture of the legs, a boom pivoted to the top of the mast extending laterally on a line between the legs, a hand hoist mounted on said boom provided with a hoist rope extending over the end of said boom, said hand hoist including a rotatable winding drum, a ratchet wheel locking the drum against reverse rotation, a second series of ratchet teeth on said wheel, and a freely revolvable hand crank provided with a pawl engaging said ratchet teeth.
- 25 5. A portable derrick comprising a pair of horizontally extending V legs close to the floor, a mast rigidly secured at the juncture of the legs, a boom pivoted to the top of the mast extending laterally on a line between the legs, a manually adjustable strut extending from the boom to the mast in a manner to be accessible for manipulation to an operative under the load supporting end of the boom, the legs and mast being of pipe, and

a multi-socket casting including an angle brace embracing and forming a rigid joint of the three members and avoiding any other bracing whereby the space over the legs is kept clear.

6. A portable derrick comprising a pair of horizontally extending V legs positioned close to the floor, a generally vertically extending mast adjacent the juncture of the legs, a boom pivoted at one end adjacent the upper end of the mast extending laterally over the area between the legs, a pulley on the boom adjacent the outer end thereof, a hand hoist mounted on said boom provided with a rope extending along the boom and over the pulley, said hand hoist being positioned at a point on the boom intermediate the pivoted end of the boom and the pulley, whereby it is accessible to an operator positioned adjacent said pulley.

7. A portable derrick comprising a pair of horizontally extending V legs positioned close to the floor, a generally vertically extending mast adjacent the juncture of the legs, a boom pivoted at one end adjacent the upper end of the mast extending laterally over the area between the legs, a pulley on the boom adjacent the outer end thereof, a hand hoist on the boom provided with a rope extending along the boom and over the pulley, said hand hoist being positioned on the boom at a point intermediate the pivoted end of the boom and the pulley whereby it is accessible to an operator positioned adjacent said pulley, a manually adjustable strut for the boom extending from the mast to a point on the boom adjacent the hand hoist and the vertical area between that portion of the boom between the hoist and pulley and the legs being free for admission of a foreign object.

8. A portable derrick comprising a pair of horizontally extending V legs close to the floor, a mast rigidly secured at the junction of the legs, a boom pivoted to the top of the mast extending laterally on a line between the legs, a manually adjustable strut extending from the boom to the mast in a manner to be accessible for manipulation to an operative under the load-supporting end of the boom, a series of teeth along said mast, and a spring acting against said strut forcing it into engagement with said teeth.
